UNITED STATES PATENT OFFICE.

FREDERICK WESSEL, OF SAN ANTONIO, TEXAS.

SIGNALING DEVICE FOR HEADLIGHTS.

No. 870,066.

Specification of Letters Patent.

Patented Nov. 5, 1907.

Application filed September 27, 1906, Serial No. 336,482. Renewed September 19, 1907. Serial No. 393,660.

To all whom it may concern:

Be it known that I, FREDERICK WESSEL, a citizen of the United States, residing at San Antonio, in the county of Bexar and State of Texas, have invented 5 certain new and useful Improvements in Signaling Devices for Headlights; and I do declare the following to be a full, clear, and exact description of the invention, such as will enable others skilled in the art to which it appertains to make and use the same.

10 This invention relates to improvements in signaling devices and more particularly one for use on a locomotive or marine head light or the like.

15 The object of the invention is to provide a head light with a simple and practical means for moving lenses of different colors into and out of its light field for signaling purposes.

20 With the above and other objects in view, the invention consists of certain novel features of construction, combination and arrangement of devices, hereinafter described and claimed.

25 In the accompanying drawings; Figure 1 is a side elevation of the improved signaling head light; and Fig. 2 is a vertical transverse sectional view taken on the plane indicated by the line 2—2 in Fig. 1.

30 Referring to the drawings by numeral, 1 denotes my improved signaling device which is mounted in a casing 2 located upon the body or casing 3 of a head light. While this head light may be of any suitable form or construction and illuminated by gas, oil or electricity, 35 the one illustrated in the drawing has a horizontally disposed cylindrical body mounted by means of brackets 4 upon a suitable base 5.

35 The casing 2 for the signaling mechanism is, as shown, of elongated, elliptical form and extends vertically at the front end of the cylindrical body 3, just in rear of the front glass or lens 6 of the head light.

40 Mounted to swing vertically within the casing 2 and the front end of the body or case 3 of the head light are one or more frames for holders carrying lenses of different colors adapted to be moved into and out of the light field or rays of light from the lamp. As shown, two of these lens holders 6 and 7 are provided, the former having a green glass or lens 8 and the latter a red one 9.

45 The holder or frame 6 is formed at a suitable point with a radially extending arm 10, pivoted upon a shaft or pivot 11 mounted in bearing brackets 12 upon the interior of the casing 2. This arm has connected to it at 13 one end of a link 14 which latter has its oppo-

site end pivoted to a long arm of a lever 15. The latter 50 is pivoted intermediate its ends upon a fixed pivot 16 within the casing and has its short end or arm connected to one end of a coil spring 17 also arranged in the casing 2 and having its opposite end secured therein as clearly shown in Fig. 2.

55 It will be seen that the spring 17 actuates the lever 15 so as to hold the lens holder or frame 6 normally elevated or in the upper portion of the casing 2 out of the field of light. Said frame or holder 6 is swung downwardly in the light field by a suitable operating 60 rod 18 connected to one arm of a bell-crank 19 which is pivoted in a bracket 20 upon the base 5 and has its opposite arm connected to a link 21 which extends through a slot or opening in the side of the casing 2 and has its upper end connected to the pivot 13 of the 65 link 14. The other lens holder or frame 7 is also formed with an arm 22 which is pivoted intermediate its ends upon the pivot or shaft 11 and has an end 23 extending through a slot in the casing 2. This end 23 of said arm is connected by a link 24 to one arm of a bell-crank 25 70 which latter has its opposite arm connected to an operating rod 26.

75 By operating the rod 26, the lens frame or holder 7 which contains the red lens or glass may be either raised out of the light field or lowered into the same. 80 This red lens holder 7 is held in its raised position by the tension of the connections by means of which it is operated, so that if any of the pins or other parts of the connections give away the lens will fall into its operative position by its own weight. The operating rods 18, 26 may extend to any place from which it is desired to operate the signals. When the red light is used for marine purposes, the rods 18, 26 are preferably omitted and keys or knobs are provided upon the levers 19 and 25.

85 It will be understood that any number of the lens frames or holders may be provided and that the lenses may be of various colors. For railroad use, I preferably employ one white, one red, and one green lens and for marine purposes the three lenses just mentioned and in addition other colored lenses and one blank or blind one.

90 From the foregoing description, taken in connection with the accompanying drawings, the construction and operation of the invention will be readily understood 95 without requiring a more extended explanation.

Various changes in the form, proportion and the minor details of construction may be resorted to with

out departing from the principle or sacrificing any of the advantages of this invention, as defined by the appended claims.

Having thus described my invention, what I claim
5 as new and desire to secure by Letters-Patent; is;—

A headlight comprising a body, a casing projecting therefrom, a lens holder disposed transversely and having an arm pivotally mounted in said casing, a lever disposed transversely and pivoted intermediate its ends in said
10 casing, a link connecting one end of said lever to said arm,

a spring connected to said casing and to the other end of said lever and serving to normally retain said lens holder out of the field of light, and an operating element connected to said arm to move said holder into the field of light against the tension of said spring.

In testimony whereof I have hereunto set my hand in presence of two subscribing witnesses.

15 FREDERICK WESSEL.
